SKIN TEST INDURATION REPORT CARD

Robert Oppenheimer, Old Greenwich, Conn., assignor to American Cyanamid Company, Stamford, Conn.

Filed Sept. 8, 1970, Ser. No. 24,877

Term of patent 14 years

Int. Cl. D24—02

U.S. Cl. D83—1

FIG. 1

FIG. 2

FIG. 1 is a perspective view of a skin test induration report card showing my new design.

FIG. 2 is a sectional view along line 2—2 of FIG. 1 showing the embossed configuration of said skin test induration report card.

The undisclosed rear side of the report card is plain.
I claim:

The ornamental design for a skin test induration report card, as shown and described.
